(57) **CLAIM**

The ornamental design for a golf club head, as shown and described.

DESCRIPTION

FIG. 1 is a bottom rear perspective view of a golf club head showing our new design;

FIG. 2 is a bottom front perspective view thereof;

FIG. 3 is a bottom view thereof;

FIG. 4 is a heel end view thereof;

FIG. 5 is a toe end view thereof;

FIG. 6 is a front view thereof; and,

FIG. 7 is a rear view thereof.

The broken line immediately adjacent to the shaded area represents an unclaimed boundary of the design. The broken line showing of the remainder of the golf club head is for illustrative purposes only and forms no part of the claimed design.
